UNITED STATES PATENT OFFICE.

ANNA J. LARSON, OF NAUGATUCK, CONNECTICUT.

PINCUSHION FOR SEWING MACHINES.

Application filed May 26, 1927. Serial No. 194,321.

This invention relates to pin holding devices, and more particularly to an improved pin cushion attachment for a sewing machine head.

5 One object of the invention is to provide a device of this character adapted to be secured to the sewing machine head at a point convenient to the operator, while at the same time so arranged as not to interfere with the 10 moving parts of the machine.

A further object of the invention is to provide a pin cushion attachment of the above nature having means for firmly securing the same to the head frame of a sewing machine 15 in such a manner that it will be retained in a fixed position at all times.

A further object of the invention is to provide a device of this nature which will be simple in construction, inexpensive to manufacture, easy to install and manipulate, compact, ornamental in appearance, and very efficient and durable in use.

With these and other objects in view, there has been illustrated on the accompanying 25 drawings one form in which the invention may be conveniently embodied in practice.

In the drawings:—

Fig. 1 represents a front plan view of the pin cushion attachment, illustrating the same 30 in extended position and detached from the sewing machine.

Fig. 2 is an end view of the same.

Fig. 3 is a front elevational view of a conventional form of sewing machine head, 35 showing the improved pin cushion attachment in operating position thereon.

Referring now to the drawings, in which like reference numerals denote corresponding parts throughout the several views, the 40 numeral 10 indicates generally the head frame of a sewing machine of conventional construction, said frame 10 being mounted upon a table 11 after the usual manner.

The head frame 10 has a substantially horizontal upper portion 12, terminating at its 45 forward end in a vertical head 13 adapted to support the needle bar 14 and needle 15, the latter being reciprocated by the usual operating mechanism within the head frame operated from the pulley 16 or hand wheel 17 50 carried by the shaft 18.

A vertical spool holding spindle 19 projects upwardly from the rear part of the horizontal portion 12 of the head frame 10 and is 55 adapted to support a spool 20 for supplying thread to the needle 15.

The pin cushion attachment comprises a supporting strip 21 formed of cloth, leather, or any other suitable flexible material, and preferably made substantially in the shape 60 of a right-angled triangle. In the embodiment herein illustrated the supporting strip 21 is formed of fabric layers 22 and 23 connected together by rows of stitches 24 and 25, as shown in Fig. 1.

A tongue or strap 26 formed of fabric layers 27 and 28 held together by a row of stitches 29 is sewed or otherwise secured to the left-hand upper corner of the triangular supporting strip 21 as viewed in Fig. 1. A 70 similar strap 30 in the form of a fabric loop is secured to the lower apex of the triangular strip 21. The looped strap 30 carries a buckle 32 having a pivoted clamp 33, and said strap is inclined from the vertical, being parallel to the inclined leg 31 of said triangular strip 21.

The tongue 26 and strap 30 may be formed from flexible sheet material which may be the same or different from the material of the 80 supporting strip 21, and said tongue and strap may be made in a single thickness within the scope of the invention.

In order to fasten the triangular supporting strip 21 to the spool holding spindle 20, 85 said strip 21 is provided at its upper right-hand corner 34 with an opening 35 in which is preferably inserted a metal eyelet 36 of suitable size to fit over said spool-holding spindle 19.

In order to form a cushion for a quantity of pins for use by the operator of the machine, provision is made of a rectangular pad 37 having a cover of cloth or other equivalent material and containing a suitable filling, such as is customarily used in pin cushions. The pad 37 is suspended from the supporting strip 21 as by a triangular-shaped tab 38 which in the embodiment illustrated herewith is formed integral with the pad 90 cover, although it may be made separate from the pad cover and secured thereto in any suitable manner if desired. The tab 38 is attached to the supporting strip by lines of stitches 39 and 40 in such a manner as to 100 allow the pin cushion pad 37 to hang freely from said supporting strip 21.

In operation, when it is desired to install the pin cushion attachment in position upon the sewing machine, the eyelet 36 of the cushion-holding strip 21 will first be slipped down over the spool spindle 19. The tongue 26

and looped strap 30 will then be wrapped about the horizontal portion 12 of the head frame, the free end of the tongue 26 being passed through the buckle 32 and adjustably secured therein by the clamp 33. In this way, the device will be securely fastened in a fixed position upon the head frame of the sewing machine, and the pin cushion pad 37 will be suspended at the most convenient place for the operator.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a pin cushion attachment for a sewing machine, a supporting strip of flexible material, cooperating means on opposite edges of said strip for encircling the head of said machine, said strip having an

eye for engaging the spool-holding spindle of the sewing machine head for holding it in fixed position, and a pin cushion pad carried by said supporting strip.

2. In a pin cushion attachment for a sewing machine, a substantially triangular supporting strip of flexible material, flexible straps attached to opposite ends of said strip for surrounding the upper horizontal head frame of the sewing machine, an eye carried by said strip for detachably securing it to a projection on said head, and a pin cushion pad carried by said strip and hanging freely therefrom.

3. In a pin cushion attachment for a sewing machine, a pin cushion supporting strip of flexible sheet material, flexible straps secured to said strip for encircling the horizontal top portion of the head frame of the sewing machine, means for detachably and adjustably connecting the ends of said straps, said strip having an eye for fitting over the spool-holding spindle of said head frame, whereby said cushion will be held in one position and will not slide along or rotate around said machine head.

In testimony whereof, I have affixed my signature to this specification.

ANNA J. LARSON.
